LASTING PIN

Forrest L. Romine, Cincinnati, Ohio

Application April 19, 1955, Serial No. 35,581

Term of patent 14 years

(Cl. D54—9)

Fig. 1

Fig. 2

Fig. 4

Fig. 5

Fig. 6

Fig. 3

Fig. 1 is a front elevational view of a lasting pin showing my new design.

Fig. 2 is a rear elevational view thereof.

Fig. 3 is a side view thereof.

Fig. 4 is a top view thereof.

Fig. 5 is a bottom view thereof.

Fig. 6 is a sectional view taken on line 6—6 of Fig. 1.

I claim:

The ornamental design for a lasting pin, as shown.
